UNITED STATES PATENT OFFICE.

LEON WYGODSKY, OF BALTIMORE, MARYLAND, ASSIGNOR TO BALTIMORE OIL ENGINE COMPANY, OF BALTIMORE, MARYLAND, A CORPORATION OF DELAWARE.

INTERNAL-COMBUSTION ENGINE AND METHOD OF BURNING FUEL-OIL THEREIN.

1,265,857.

Specification of Letters Patent. Patented May 14, 1918.

Application filed May 31, 1916. Serial No. 100,769.

To all whom it may concern:

Be it known that I, LEON WYGODSKY, a subject of the Czar of Russia, and a resident of the city of Baltimore, Maryland, have invented certain new and useful Improvements in Internal-Combustion Engines and Methods of Burning Fuel-Oil Therein, of which the following is a specification.

My invention relates to improvements in internal combustion engines, particularly engines of the so-called two cycle type, and comprises a novel construction of cylinder, cylinder head, and piston, whereby improved scavenging of the engine is effected, together with increased economy in fuel consumption, and whereby other desirable results are realized. My invention further comprises improved means for the production at the end of the compression stroke, of a small quantity of highly compressed air at a pressure suitable for the operation of a sprayer for spraying fuel into the engine cylinder. Other features of my invention will be pointed out hereafter.

The objects of my invention are, to improve the scavenging of two cycle engines; to insure practically complete separation of the burnt gases from the incoming air; to obtain better flow of the air into the engine cylinder, and a more effective sweep of the burnt gases by that air out of the engine cylinder; to effect such scavenging without material loss of the air through the exhaust port of the engine cylinder; to avoid leakage into the exhaust port of the engine cylinder, of the air compressed in that cylinder; to provide an easy sweep for the gases through and out of the engine cylinder, and to so arrange the ports of the engine that the incoming charge and the out-flowing burnt gases shall flow in one direction only, thereby to a large extent preventing mixture of air with the burnt gases; to utilize the inertia of the burnt gases to empty the engine cylinder of such gases, and to use the inertia of the incoming air to fill the cylinder with such air and to induce a current of extra air from the crank case; and to provide improved means for compression to a high degree, within the engine cylinder, of air for the operation of a fuel spraying device; also to obtain high compression in the engine cylinder, as is desirable for use of heavy oil fuel.

I will now proceed to describe my inven-

tion with reference to the accompanying drawings, and will then point out the novel features in claims:

In said drawings:

Figure 1 shows a central vertical section 60 of a two cycle engine embodying my invention.

Fig. 2 shows a transverse section on the line 2—2 of Fig. 1, and

Fig. 3 shows a transverse section on the line 3—3 of Fig. 1.

Referring first to Fig. 1: The engine shown therein is of the crank case compression type, and comprises a crank case bottom member 1, a crank case top and cylinder base 2, a cylinder proper 3, a cylinder head 4, a piston 5, a crank shaft 6 and a connecting rod 7. The cylinder head 4 is provided with a portion 8 projecting into the top of the engine cylinder, which projecting portion is hollow, for lightness and in order that there may not be too great thickness of metal. The cylinder is provided with the usual cooling jacket 9, and the cylinder head may also be provided with a cord recess 10 through which cooling water may be circulated. The cylinder is provided with an exhaust port or belt 11, which in this case is located at the top of the main portion of the engine cylinder, instead of being located at the bottom of such cylinder as is common in two cycle engine practice. This exhaust port or belt extends completely around the engine cylinder as indicated particularly in Fig. 2, and is connected with the engine cylinder by spaces between ribs 12 forming a part of the engine cylinder. The engine is provided with a transfer port 13 extending completely around the engine cylinder, the lower sleeve portion 14 of the engine cylinder being connected to the outer wall of the cylinder structure by ribs 15 shown in Fig. 3.

The piston 5 is provided with a piston head 16, tapering upwardly or toward the rear, and is further provided with a valve-sleeve extension 17 working in the narrow annular space between the cylinder walls and the inwardly projecting portion 8 of the cylinder head; and the piston is further provided between this sleeve portion 17 and the piston head 16, with an inwardly projecting curved boss 18, there being, between the bottom of this boss and the piston head 16, a port-passage 19 adapted to coact with the 110

transfer port 13 so that, when the port passage 19 registers with the transfer port 13, air under more or less pressure may flow through the port passage 19 toward the central portion of the cylinder. Owing to the curved form of the inner surface of the boss 18, and the correspondingly curved and upwardly-tapering form of the piston head 16, the air, thus directed inwardly into the cylinder, is permitted to spread out, as it moves upward or backward in the cylinder, forcing before it the burnt gases already in the cylinder. Because of the curved tapering form of the lower portion of the cylinder head projection 8, and because of the curved form of the upper portion of the boss 18, the burnt gases, so swept upward by the entering air, are caused to flow outward toward the exhaust port 11. I thus achieve a natural inward and upward or backward flow of the entering air followed by an outward flow of the air within the engine cylinder, such as causes such entering air to fill the engine cylinder first at the bottom and thence upward, and I also achieve a natural upward or backward and outward flow of the burnt gases in advance of the entering air; a condition which creates very perfect scavenging of the engine cylinder while avoiding any material mixture of the entering air with the burnt gases. This is very important, because complete scavenging of two-cycle engines is of course very desirable, but as is well known, has not been attained effectively in the past, except possibly by the use of special scavenging means in addition to the action of air admitted from the crank case. It is well known that the form of the parts within the engine cylinder affect very greatly the flow of the incoming air and the flow of the outgoing burnt gas. The form of the piston, including its head 16, its sleeve 17, and its boss 18, and the form of the lower tapering portion of the cylinder head projection 8, are such, in my engine, as to produce more perfect scavenging than has ever been effected before to my knowledge. In addition, since the entering air and the outgoing burnt gases flow, in general, in one direction only, and without material swirling, the inertia of these gases aids greatly in the complete expulsion of the burnt gases and the complete filling of the engine cylinder with air uncontaminated with exhaust gases; also, the inertia of the entering air tends to draw into the engine cylinder a quantity of air in excess of the cubic contents of that cylinder at atmospheric pressure. In other words, the cylinder receives a super-charge of pure air.

In the drawing, the piston is shown at the top of its stroke. Near the end of its forward or downward stroke, the upper edge of the sleeve extension 17 of the piston un-65 covers the exhaust port 11, whereby the

burnt gases in the engine cylinder escape, the pressure in such cylinder being reduced greatly; and after this exhaust port 11 has been opened somewhat, and a current of out-flowing gas established in the exhaust line, 70 the ports 19 of the piston communicate with the transfer port 13, permitting air compressed in the crank case by the piston in its downward movement, to pass into the engine cylinder. Such air is directed by the 75 ports 19 of the piston inwardly and upwardly. Since by the previous opening of the exhaust port 11, the exhaust gases in the engine cylinder are already flowing upwardly and outwardly into that exhaust 80 port, the compressed air as it enters merely assists this outward sweeping of the burnt gases, driving them up and out of the lower portion of the cylinder toward the exhaust port; there being little or no occasion for 85 swirling motion of either the air entering the engine cylinder or the burnt gases passing from the engine cylinder, and therefore little occasion for mixing of the air with the burnt gases; particularly in view of the already 90 established current of burnt gases, as already mentioned. In fact, it is desired, so far as possible, to maintain complete stratification between the burnt gases and the entering air.

The valve sleeve 17 of the piston, in moving up through the annular space between cylinder head projection 8 and the walls of the cylinder, compresses air at the top of this annular space; and the length of this sleeve 17 is such that at the top of the stroke 95 the clearance space in such annular space is less in proportion than the clearance space in the main portion of the engine cylinder; and as a result air is compressed, at the top of this annular space, to a higher degree than 100 the compression in the main portion of the engine cylinder. This higher compression at the top of the annular space in which the sleeve 17 works, is of advantage for several reasons; first of all it tends to prevent loss 105 of air in the main compression space of the engine cylinder by leakage around the sleeve 17; and furthermore, the air so compressed in the annular space is useful in spraying fuel oil into the engine cylinder. While of course a combustible charge might be drawn into the crank case 2 and thence passed through the transfer port 13 into the engine cylinder, I prefer to admit pure air only into the crank case and thence through the transfer port into the engine cylinder, and to provide a sprayer 20 in the cylinder head. This sprayer may be of any of the usual types, and may receive its oil or fuel through a pipe 21, the oil being forced through that 115 pipe 21 and the flow of such oil being regulated by any suitable means, for example, the governor-controlled pump of my Patent No. 971,954 dated October 4, 1910. While according to that patent the oil is sprayed 120

by pressure produced by the pump, it is convenient to employ compressed air for effecting a finer atomization of the oil and a wider spread of the oil entering the combustion space of the engine cylinder; and this is accomplished by my present invention, air, compressed to a higher degree than the compression in the main clearance space of the engine cylinder, being passed from the 5 annular compression space in which valve sleeve 17 works, through a pipe 22, into the sprayer. Sprayers operating both by compressed air and by the pressure of oil positively supplied, as by means of gravity or by 10 a pump, are known, and therefore I do not consider it necessary to illustrate herein the details of the sprayer 20.

Any of the ordinary means may be employed for admitting air to the crank case 2, 20 and therefore I have not thought it necessary to illustrate any particular means for that purpose herein. One well known means is an inwardly opening check valve located in a suitable port in the crank case, and another well known means is a port or ports in 25 the cylinder wall arranged to be uncovered at suitable times by the piston—as in the so-called three-port two-cycle engine.

In some cases, two cycle engines are provided with compression chambers, other than 30 a crank case, and with supplementary pistons for such compression chambers, operated by the main engine piston. I have not thought it necessary to illustrate such a construction in connection with the engine herein illustrated and described, for the reason 35 that such supplemental compression spaces with supplemental pistons are, in a broad sense, the mere equivalent of the crank-case compression space wherein air is compressed by the main piston. It will be obvious to those skilled in the art how such a 40 supplemental compression device may be applied to my engine in lieu of the employment of crank case compression.

In a broad sense it is immaterial in an engine such as herein described, whether the transfer port open into the engine cylinder near the lower or outboard end thereof, and the exhaust port open from the engine cylinder near the upper or inboard end thereof, or whether the reverse be the case. Both types of engine are known, and it will be obvious to those skilled in the art that in 55 my engine the positions of the transverse port and exhaust port might be reversed. Location of the transfer port near the lower or outboard end of the cylinder possesses many structural advantages, however, and 60 so is preferred.

I have designed this engine with a view to the use, primarily, of heavy oil fuel. For the use of such fuel relatively high compression in the engine cylinder is desirable; for 65 example, a pressure in excess of 150 pounds

per square inch. Obviously, in order that such high compression may be obtained, the clearance space in the engine cylinder, at the end of the upstroke of the piston, must be very small. I am aware of prior patents 70 showing engines having an admission port at the lower end of the cylinder and an exhaust port at the upper end of the cylinder and arranged to be uncovered or opened, near the lower end of the piston stroke, by 75 a valve sleeve extension of the piston. It has not been practicable, heretofore, to use such a construction in an engine designed to have high compression, because, if the piston approach the cylinder head so nearly as is 80 required for high compression, the admission port of the piston will open the exhaust port, and as a consequence the engine will lose its compression altogether. In my engine, by reason of the tapering form of the 85 lower portion of the cylinder projection 8, of the piston head, the exhaust port of the engine cylinder may be placed well above the lower termination of this cylinder head projection, and therefore the admission port 90 19 of the piston will not open the exhaust port even though, as in the design shown in the accompanying drawings, the piston head approach practically to the lower termination of the cylinder head projection, at the 95 end of the compression stroke of the piston.

As the boss 18 of the piston nears the tapering portion of the cylinder head projection 8, there is a peculiar action which tends to assist greatly the spreading out of the 100 spray of fuel oil injected at about that time by the sprayer 20; for, since at the end of the compression stroke, the space between this boss 18 and the cylinder head projection 8 is very small indeed, air is forced out 105 of this space downward into the main compression space of the engine cylinder, producing a flow of air at this point in opposition to the natural flow of air in the engine cylinder due to the upstroke of the piston, 110 whereby a swirling motion is set up in the main compression space, facilitating very greatly the mixture of the oil with the air in the compression space.

Because the boss 18 is not in contact with 115 the water cooled cylinder wall, and therefore may become somewhat highly heated, it aids materially in vaporization of the oil injected into the compression space.

What I claim is:

1. An internal combustion engine comprising in combination an engine cylinder having near its opposite ends two ports, one adapted to serve as an exhaust port and the other as a transfer port, a piston within the cylinder and provided with a sleeve extension adapted to travel across the rearward of such ports to open and close the same, said piston having a port adapted to open and close the forward of said cylinder ports, 125 130

said cylinder having also a head provided with a projection extending longitudinally into the cylinder to a point beyond that cylinder port which is proximate to such head, such projection spaced away from the cylinder walls to provide a space for the travel of the sleeve extension of such piston, and further spaced away from the path of such sleeve projection from about the rear limit of the rear cylinder port, to provide a clear passage for the flow of gases through such port; said engine further comprising a compression chamber wherein air may be compressed by motion of the piston, and a duct connecting such compression chamber with said transfer port;

2. An internal combustion engine comprising in combination an engine cylinder having near its opposite ends two ports, one adapted to serve as an exhaust port and the other as a transfer port, a piston within the cylinder and provided with a sleeve extension adapted to travel across the rearward of such ports to open and close the same, said piston having a port adapted to open and close the forward of said cylinder ports, said cylinder having also a head provided with a projection extending longitudinally into the cylinder to a point beyond that cylinder port which is proximate to such head, such projection spaced away from the cylinder walls to provide a space for the travel of the sleeve extension of such piston, and further spaced away from the path of such sleeve projection from about the rear limit of the rear cylinder port, to provide a clear passage for the flow of gases through such port, said piston provided with an inward projection arranged to approach closely the sides of said cylinder head projection when the piston is near the rearward limit of its stroke, whereby the clearance space is reduced; such engine further comprising a compression chamber wherein air may be compressed by motion of the piston, and a duct connecting such compression chamber with said transfer port.

3. An internal combustion engine comprising in combination an engine cylinder having near its outboard end a transfer port and having near its inboard end an exhaust port, a piston within the cylinder and provided with a sleeve extension adapted to travel across said exhaust port to open and close the same, said piston having also a port adapted to open and close the transfer port, said cylinder having also a head provided with a projection extending longitudinally into the cylinder to a point beyond the exhaust port, such projection spaced away from the cylinder walls to provide a space for the travel of the sleeve extension of such piston, and tapering inward from about the rear limit of the rear cylinder port to provide a clear passage for the flow of gases through such port; said engine further comprising a compression chamber wherein air may be compressed by motion of the piston, and a duct connecting such compression chamber with said transfer port.

4. An internal combustion engine comprising in combination an engine cylinder having near its outboard end a transfer port and having near its inboard end an exhaust port, a piston within the cylinder and provided with a sleeve extension adapted to travel across said exhaust port to open and close the same, said piston having also a port adapted to open and close the transfer port, said cylinder having also a head provided with a projection extending longitudinally into the cylinder to a point beyond the exhaust port, such projection spaced away from the path of such sleeve projection from about the rear limit of the exhaust port to provide a clear passage for the flow of gases through such port; said engine further comprising a compression chamber wherein air may be compressed by motion of the piston, and a duct connecting such compression chamber with said transfer port.

4. An internal combustion engine comprising in combination an engine cylinder having near its outboard end a transfer port and having near its inboard end an exhaust port, a piston within the cylinder and provided with a sleeve extension adapted to travel across said exhaust port to open and close the same, said piston having also a port adapted to open and close the transfer port, said cylinder having also a head provided with a projection extending longitudinally into the cylinder to a point beyond the exhaust port, such projection spaced away from the cylinder walls to provide a space for the travel of the sleeve extension of the piston and further spaced away from the path of such sleeve projection from about the rear limit of the exhaust port, to provide a clear passage for the flow of gases through such port, said piston provided with an inward projection arranged to approach closely the sides of said cylinder head projection when the piston is near the rearward limit of its stroke, whereby the clearance space is reduced; such engine further comprising a compression chamber wherein air may be compressed by motion of the piston, and a duct connecting such compression chamber with said transfer port.

5. An internal combustion engine comprising in combination an engine cylinder having near its opposite ends two ports, one adapted to serve as an exhaust port and the other as a transfer port, a piston within the cylinder and provided with a sleeve extension adapted to travel across the rearward of such ports to open and close the same, said piston having a port adapted to open and close the forward of said cylinder ports, said cylinder having also a head provided with a projection extending longitudinally into the cylinder to a point beyond the cylinder port which is proximate to such head, such projection spaced away from the cylinder walls to provide a space for the travel of the sleeve extension of such piston, and tapering inward from about the rear limit of the rear cylinder port to provide a clear passage for the flow of gases through such port; said engine further comprising a compression chamber wherein air may be compressed by motion of the piston, and a duct connecting such compression chamber with said transfer port.

6. An internal combustion engine comprising in combination an engine cylinder hav-

ing near its opposite ends two ports, one adapted to serve as an exhaust port and the other as a transfer port, a piston within the cylinder and provided with a sleeve extension adapted to travel across the rearward of such ports to open and close the same, said piston having a port adapted to open and close the forward of said cylinder ports, said cylinder having also a head provided with a 5 projection extending longitudinally into the cylinder to a point beyond that cylinder port which is proximate to such head, such projection spaced away from the cylinder walls to provide a space for the travel of the sleeve extension of such piston, and tapering inward from about the rear limit of the rear cylinder port, to provide a clear passage for the flow of gases through such port; said piston provided with an inward projection 10 arranged to approach closely the sides of said cylinder head projection when the piston is near the rearward limit of its stroke, whereby the clearance space is reduced; such engine further comprising a compression 15 chamber wherein air may be compressed by motion of the piston, and a duct connecting such compression chamber with said transfer port.

7. An internal combustion engine comprising in combination an engine cylinder having near its outboard end a transfer port and having near its inboard end an exhaust port, a piston within the cylinder and provided with a sleeve extension adapted to 20 travel across said exhaust port to open and close the same; said piston having also a port adapted to open and close the transfer port, said cylinder having also a head provided with a projection extending longitudinally 25 into the cylinder to a point beyond the exhaust port, such projection spaced away

from the cylinder walls to provide a space for the travel of the sleeve extension of the piston and tapering inward from about the rear limit of the exhaust port to provide a 45 clear passage for the flow of gases through such port, said piston provided with an inward projection, the rear side of which is shaped to correspond with the tapering portion of the cylinder head projection and is 50 adapted to approach the same closely when the piston is near the rearward limit of its stroke, whereby the clearance space is reduced, and the front portion of which piston projection is curved; the piston head tapering rearwardly and forming with the proximate portion of the inward projection of such piston, a rearwardly curved passage arranged to direct gases entering through the transfer port toward the center and rear 55 of the cylinder; said engine further comprising a compression chamber wherein air may be compressed by motion of the piston, and a duct connecting such compression chamber with said transfer port. 60

8. The herein described method of burning fuel oil in an internal combustion engine, which comprises compressing air in such engine, injecting fuel oil into such air, and at about the time of such injection, forcing air under higher pressure toward and around the injected stream of oil, and thereby producing a swirling motion of the oil and air. 65

In testimony whereof I have signed this 70 specification in the presence of two subscribing witnesses.
